CLAIM

The ornamental design for an egg poacher, as shown and described.

DESCRIPTION

FIG. 1 is a perspective view of an egg poacher, showing my new design;

FIG. 2 is a front elevation view thereof;

FIG. 3 is a side elevation view thereof;

FIG. 4 is a top plan view thereof; and,

FIG. 5 is a bottom plan view thereof.

The broken lines are for illustrative purposes only and form no part of the claimed design.
